UNITED STATES PATENT OFFICE.

R. NICKSON, OF AKRON, OHIO.

IMPROVEMENT IN CARRIAGE-TOP PROTECTORS.

Specification forming part of Letters Patent No. **59,056**, dated October 23, 1866.

To all whom it may concern:

Be it known that I, R. NICKSON, of Akron, Summit county, and State of Ohio, have invented a new and Improved Carriage-Top Protector; and I do hereby declare that the following is a full, clear, and exact description thereof, which will enable others skilled in the art to make and use the same, reference being had to the accompanying drawings, forming part of this specification.

The object of the present invention is to prevent and obviate the wearing away of the tops of carriages when let down, as is now the case with the use of the well-known and familiar prop-blocks; and for this purpose it consists in a novel-constructed device or protector for carriage-tops, which will be now described, reference being had to the accompanying plate of drawings, in which—

Figure 1 is a side view of the protector embraced in the present invention; and Fig. 2, a transverse vertical section, taken in the plane of the line $\alpha\alpha$, Fig. 1.

Similar letters of reference indicate like parts.

A in the drawings represents a block of wood or other suitable material of about three and a half inches in length, which block is made with a groove, B, along one side. On this grooved side of the block A three or more spiral conical or helical springs, C, are secured by their larger ends, upon which, at the upper and smaller ends, a narrow plate, D, is secured to each spring in any suitable manner.

This protector, constructed as above explained, is to be covered upon all sides with leather or other suitable material, and when properly applied to a carriage must necessarily prevent its top from wearing away when lowered, as is obvious without any further explanation.

I claim as new and desire to secure by Letters Patent—

A protector for carriage-top formed of a grooved block, A, spring C, and plate D, substantially as described.

R. NICKSON.
